UNITED STATES PATENT OFFICE.

LEWIS HARNISH, OF PARKERSBURG, WEST VIRGINIA.

WINDOW-SHADE BRACKET.

SPECIFICATION forming part of Letters Patent No. 450,070, dated April 7, 1891.

Application filed November 8, 1890. Serial No. 370,762. (No model.)

To all whom it may concern:

Be it known that I, LEWIS HARNISH, a citizen of the United States, residing at Parkersburg, in the county of Wood and State of 5 West Virginia, have invented new and useful Improvements in Window-Shade Brackets, of which the following is a specification.

My invention is directed to an improved bracket device for the hangings of window-shades which are movable with the upper sash, and the precise improvement which I have made consists in the particular construction of the bracket, whereby it is secured to the upper sash and to a bar to which the bearings of a roller shade are secured, as illustrated in the accompanying drawings, in which—

Figure 1 is a vertical section of so much of the upper window-sash and its framing as 20 illustrates the application to the sash of my improved bracket-hanger for the roller shade. Fig. 2 is a horizontal section showing the roller-shade-bracket hangers in top view, and Fig. 3 is the bracket-hanger in elevation.

The shade-roller *a* is mounted in the usual bracket-bearings *b*, which are secured to each end of a bar *c*, which is secured at each end to the window-sash by my improved bracket-hangers, as I will now describe. The bracket 25 consists of a claw-arm part *d*, having one end formed with an L-shaped bend *d'*, terminating in a claw *d''*, adapted to be driven into the top of the sash, with the bend *d'* resting against the side of the sash. Its other end is formed 30 with a sleeve part *d³*, from which extends a lower pointed part *d⁴*, adapted to be driven into the side of the sash. An extensible L-shaped part *e* is fitted into the sleeve part *d³* with the L branch standing upward, and

serves as a pintle upon which the roller bar 40 is hung by means of a hinge part *e'*, secured to the inner side of said roller bar.

One of these bracket-hangers is secured to the upper bar of the upper sash at each side of the window-frame, and a half hinge-leaf is 45 secured to each end of the roller bar in position to be fitted upon the pintle ends of the extensible bracket parts, which can be set in or out upon the claw parts to suit the depth of the window-jambs. A set-screw *f* secures the 50 extensible part to the claw part. The hinge-leaf part can be made of flexible metal lapped to form the pintle-eye. The nail part has a shoulder *d⁵* by which it is driven into the sash, and this nail part while serving to re-enforce 55 the hold of the claw-bar also serves as a brace to support the weight of the shade and its roller.

I claim as my improvement—

The window-shade bracket herein described, consisting of two extensible parts, one of which has an arm part *d*, provided at one end with a sleeve *d³* and at its other end with an L-bend terminating in a downward claw *d''*, and a brace terminating in a nail *d⁴*, 65 the other part *e* having a U pintle end standing upward, in combination with the bar *c*, having on one side the pintle-eyes *e' e'* at each end, and on the other side of the bracket bearings *b* at each end for the shade-roller, 70 as shown and described.

In testimony whereof I have hereunto set my hand in the presence of two subscribing witnesses.

LEWIS HARNISH.
